UNITED STATES PATENT OFFICE.

HAROLD KENNEY BEACH AND NEALON AUSTIN BEACH, OF BALTIMORE, MARYLAND,
ASSIGNORS TO BALTIMORE TUBE COMPANY, INCORPORATED, A CORPORATION OF
MARYLAND.

PICKLING PROCESS AND APPARATUS.

1,402,734.

Specification of Letters Patent. Patented Jan. 10, 1922.

Application filed November 4, 1920. Serial No. 421,632.

To all whom it may concern:

Be it known that we, HAROLD KENNEY BEACH and NEALON AUSTIN BEACH, citizens of the United States, residents, respectively, 5 of Baltimore, in the county of Baltimore, State of Maryland, have invented a new and useful Pickling Process and Apparatus, of which the following is a specification.

Our invention relates to improvements in 10 pickling process and apparatus. The object is to provide improved method and means for passing the metal through the several baths in the pickling and washing operations.

15 The invention comprises improved method and means for introducing and withdrawing the metal from the several baths in the most convenient and expeditious way and with a minimum of labor.

20 Referring to the drawings, which illustrate, merely by way of example suitable means for effecting our invention—

Fig. 1 is a plan view of apparatus embodying our invention.

25 Fig. 2 is a side elevation of same.

Fig. 3 is a vertical section on line 3, 3 of Fig. 1.

Fig. 4 is a transverse vertical section on line 4, 4 of Fig. 1, on an enlarged scale.

30 Fig. 5 is a sectional detail showing operating levers for clutches.

Similar numerals refer to similar parts throughout the several views.

In Fig. 3, we have shown the general 35 scheme of passing the metal into and from the several baths to the drier or directly to a suitable arbor or reel for receiving same. In the present example the metal to be treated is shown as strips of sheet metal 40 formed into coils. Metal in other forms can obviously be treated in a similar way.

The tank 7 is provided with a suitable acid in which the metal 8 is first immersed. The free end of the sheet of metal 8 is then 45 carried over roller 9 and secured to the winding arbor or spool 10 in the usual way, by inserting the end of the metal into a slot in said arbor or spool.

Spool 10 is mounted, on frame 11. This 50 frame 11, is mounted on shaft 12, which carries at its other end the spool 13, which is shown as projecting into the cold water tank 14. A similar spool frame 15 is mounted on shaft 16 over the hot wa-

ter tank 17 and is provided in a similar way with the spools 18 and 19. Roller 20 serves to support and guide the metal passing from spool 13 to spool 18, and roller 21 supports and guides the metal passing from spool 19 to suitable drying apparatus or directly to another arbor or spool not shown.

In operation the metal 8 having been immersed in the acid in tank 7 is wound onto spool 10. In the complete operation of the 65 means herein shown it will be assumed that metal had been previously wound onto spool 13 from tank 7 while spool 13 was in the position in which spool 10 is now shown, after which frame 11 is given a half rotation 70 carrying spool 10 from tank 14 and spool 13 into tank 14 in the position as now shown.

It will be understood that one end of the metal wound on spool 13 and now immersed in the cold water tank 14, is passed over 75 roller 20 and secured to spool 18 mounted on frame 15. It will also be understood that in a similar way spool 19 had been previously wound with metal before immersion into hot water tank 17 as 80 shown, and that its free end has been passed over roller 21 to a suitable receiving device not shown.

With the arrangement above described, a suitable controlling mechanism is operated 85 which causes the rotation of spools 10 and 18, which results in the winding of the metal 8 from tank 7 onto spool 10, and the winding of the metal from spool 13 in tank 14, onto spool 18. It 90 is also presumed that a suitable receiving device has been provided for taking care of the metal on spool 19, but this is not a part of the present invention and is therefore not shown.

When this operation has been accomplished, frame 11 is given a one-half rotation, carrying loaded spool 10 into the cold water tank 14 and the empty spool 13 out of the cold water into the position formerly assumed 100 by spool 10. At the same time frame 15 is similarly rotated thereby reversing the positions of spools 18 and 19. The device is now in position for repeating the operation above described, that is to say, a fresh 105 coil of metal is immersed in acid tank 7, the end of the metal is passed over roller 9 and secured to spool 13. The end of the metal,

now coiled on spool 10 and immersed in cold water tank 14, is passed over roller 20 and secured to empty spool 19, while the end of the metal loaded onto spool 18, now immersed in the hot water tank 17, is passed over roller 21 and connected with any suitable receiving device not shown. By the arrangement above described it will be observed that while one charge of metal is being withdrawn from the acid tank, another charge is simultaneously withdrawn from the cold water tank and still another charge withdrawn from the hot water tank. It will also be seen that after each operation the empty spools are simultaneously lifted from the tanks and the loaded spool immersed in said tanks.

The means for rotating the spools and the spool frames, and the controls therefor, which makes possible the said operations, will now be described.

Referring to Fig. 1, the shaft 22 receives its power from the motor 23, or other suitable source of power, and distributes this power to shafts 24 and 25. Shafts 24 and 25 rotate continuously and drive the spools through the clutches 26 and 27. Power is transmitted from shaft 24 to shafts 12 and 16, which rotate the spool frames 11 and 15, through the following mechanism; shaft 24 drives shaft 30 through sprocket chain 31. Shaft 30 drives shaft 32 through spiral gears 33. Shaft 32 drives shafts 12 and 16 by means of the worm gears 34 and 35, and the clutches 36 and 37.

The clutch elements 36 and 37 are the ordinary one-turn clutches commonly used in slow speed press construction, except that cams 38 are provided so that they will knock out every half revolution. Elements 36 are loosely mounted on shafts 12 and 16 respectively and rotate continuously. Elements 37 are feathered on their respective shafts, so that when element 36 engages element 37 the shafts rotate; and when the elements are disengaged the shafts stop. Normally elements 37 are held disengaged from elements 36 by means of pin 39 engaging with the cam 38 connected with element 37. When pin 39 is withdrawn from cam 38, the spring 40 forces element 37 into engagement with element 36, thereby causing the rotation of the shafts and the spool frames. As the shaft rotates, pin 39, having returned to its position by the action of the spring 41, engages the cam 38 and thereby causes the separation of the clutch elements 36 and 37, and the stopping of the rotation of the shafts 12 and 16. These shafts 12 and 16 are locked in position of rest by the latch 42 which engages one of the slots 43 in the disc 44, which is also keyed to the shaft. The latch 42 is normally actuated by spring 45 to engage with a slot 43, when the same comes into register therewith.

The pin 39 is mounted on rod 58 connected with lever 57 (see Fig. 5) mounted on shaft 56. The latch 42 is connected to the rod 60, which is connected to a similar lever, as 57, mounted on shaft 56. Shaft 56 is operated by the lever 52 and pedal 51 as herein-after described.

The clutch elements 26 and 27 are controlled by the bell lever 46 connected by the rod 47 to lever 55 mounted on shaft 54, see Fig. 5. Shaft 54 is operated by pedals 49, 50 and 51, as herein-after described.

In operation after the metal strips have been connected with the empty spools which are above the tanks as above described, the pedal 49 on shaft 54, controlling the clutch elements 26 and 27, is operated to bring these clutch elements into engagement. This causes the winding of the metal from the several tanks, onto the empty spools 85 10 and 18 as shown in Fig. 3. After the metal has been wound entirely upon these spools, the pedal 50, also on shaft 54, is actuated to rock the shaft in the opposite direction, to cause the separation of the 90 clutch elements 26 and 27. This stops the rotation of the spools. The pedal 51 loosely mounted on shaft 54, but adapted to engage lever 52 on shaft 56, is then actuated to cause the withdrawal of the latch 42 from 95 a slot 43 of disc 44, and the pin 39 from the cam 38. This permits the engagement of clutch elements 36 and 37, and permits the rotation of shafts 12 and 16. This results in a half rotation of the spool frames 100 11 and 15, and causes the loaded spools or charges to be immersed, one in the cold water tank and the other in the hot water tank, while the empty spools are lifted above the tanks. After the several pieces or sheets of metal 105 are connected to the empty spools, the operation is repeated as above described.

It will be noted that the arrangement of pedals is such that the operation of pedal 49 causes the engagement of clutches 26 and 27. Pedal 50 may be operated independently of pedal 51 to cause the separation of clutch elements 26 and 27. The operation of pedal 51 causes the withdrawal of pin 39 and latch 42. Pedal 51 is idly mounted on 115 shaft 54 and has an extension overlying a projection 50' from pedal 50, so that unless pedal 50 has been previously depressed, pedal 51 will depress the same, when operated to depress lever 52 on shaft 56. The result of this arrangement is that shaft 56 cannot be rocked to cause the withdrawal of pin 39 and latch 42, until the shaft 54 has been rocked to cause the separation of clutch elements 26 and 27.

What we claim is:—

1. The method of pickling which consists in introducing coils of metal into a plurality of baths, simultaneously withdrawing the metal by winding the coils from the sev- 130

eral baths, and then simultaneously immersing coils so withdrawn into other baths respectively, and progressively winding one coil from the last bath as each new coil is

5 withdrawn from the first bath.

2. In a pickling device, the combination of a plurality of liquid containers, a plurality of rotatable spool frames with spools mounted thereon, so arranged that when 10 one spool of a frame is immersed in the liquid another spool is above the liquid, means for rotating the spools, means for rotating the frames and means for arbitrarily controlling the rotating means.

15 3. In a pickling device, the combination of a plurality of liquid containers, a plurality of rotatable spool frames with spools mounted thereon, so arranged that when one spool of a frame is immersed in the liquid 20 another spool is above the liquid, means for simultaneously rotating the spools and arbitrarily operated means for controlling said rotating means.

4. In a pickling device, the combination 25 of a plurality of liquid containers, a plurality of rotatable spool frames with spools mounted thereon, means for rotating the frames to carry the spools into and out of the liquid and means for arresting the 30 frames in required position.

5. In a pickling device, the combination 35 of a plurality of liquid containers, a plurality of rotatable spool frames with spools mounted thereon, means for rotating the frames, comprising a constantly rotating element and a clutch between the constantly 40 rotating element and the frame, and arbitrarily operated mechanism for controlling the clutch.

40 6. In a pickling device, the combination of a plurality of liquid containers, a plurality of rotatable spool frames with spools mounted thereon, means for rotating the spools, comprising constantly rotating ele-

ments and a clutch between said constantly 45 rotating elements and the spool, and an arbitrarily operated lever for controlling the clutch.

7. In a pickling device, the combination of a plurality of liquid containers, a plurality of rotatable spool frames with spools mounted thereon, means for rotating the frames, comprising a constantly rotating element and a clutch between the constantly 50 rotating element and the frame, arbitrarily 55 operated mechanism for controlling the clutch, a latch for locking the frame in required position, and means for arbitrarily controlling the latch, operating simultaneously with the clutch control. 60

8. In a pickling device, the combination of a plurality of liquid containers, a plurality of rotatable spool frames with spools mounted thereon, means for rotating the spools, including cooperating clutch elements, means for rotating the frames including other cooperating clutch elements, and interacting mechanism whereby the means for bringing into operative relationship the frame clutch elements can only be 65 operated after the mechanism separating the spool clutch elements has operated. 70

9. In a pickling device, the combination of a plurality of liquid containers, a plurality of rotatable spool frames with spools 75 mounted thereon, means for rotating the spools, including cooperating clutch elements, means for rotating the frames including other cooperating clutch elements, a latch for locking the frame in desired 80 position, and interacting mechanism whereby the means for bringing into operative relationship the frame clutch elements and for releasing the latch can only be operated after the mechanism separating the spool 85 clutch elements has operated.

HAROLD KENNEY BEACH.
